UNITED STATES PATENT OFFICE.

NOBLE G. BOWLES, OF PADEN, OKLAHOMA.

WELL-BUCKET.

1,208,901.

Specification of Letters Patent. Patented Dec. 19, 1916.

Application filed December 15, 1915. Serial No. 66,998.

To all whom it may concern:

Be it known that I, NOBLE G. BOWLES, a citizen of the United States, residing at Paden, in the county of Okfuskee and State of Oklahoma, have invented certain new and useful Improvements in Well-Buckets, of which the following is a specification, reference being had to the accompanying drawings.

This invention relates to improvements in well buckets and has for its primary object to provide a bucket for use in tube or bored wells provided with valves in its base which open upon the downward movement of the bucket into the water and enable the bucket to quickly fill, said valves being so constructed and arranged that the contents of the bucket may be discharged into a receptacle without necessitating the manual manipulation of the valves.

It is another and more particular object of the invention to provide a well bucket having spaced openings in its bottom and valves normally closing the same, each of said valves having a rod, manually operable means to which the rods are connected and with respect to which they are relatively novable, one of the valve rods being projected below the valve and adapted to engage the bottom of a receptacle, whereby the valve is opened.

It is a further object of the invention to construct a well bucket provided in its base with two discharge openings, a funnel-shaped pout projecting downwardly from one of the openings through which the contents of the bucket may be directed into a receptacle having a contracted mouth, valves normally closing said openings, and manually operable means mounted in the head of the bucket for opening either of said valves.

With the above and other objects in view, my invention consists in the novel features of construction, combination and arrangements of parts to be hereinafter more fully described, claimed, and illustrated in the accompanying drawing, in which,

Figure 1 is a vertical longitudinal section through a well bucket, illustrating the preferred embodiment of my invention; Fig. 2 a section taken on the line 2—2 of Fig. 1; Fig. 3 is a sectional view of the receptacle showing the bucket arranged therein, the lower end of the bucket being also shown in section.

Referring in detail to the drawing, 5 des-

ignates the cylindrical, tubular body of the bucket having a body or base wall 6 provided with the spaced openings 7 and 8 of relatively different sizes therein. At the 60 edge of each opening a raised valve seat, indicated at 9 and 10, respectively, is formed.

Within the bucket a vertical frame 11 is mounted, said frame being suitably fixed at its lower end to the base or bottom wall of the bucket. This frame includes transverse bars 12, each of said bars having openings formed therein through which the valve rods 13 and 14 are loosely disposed. To the lower end of each of said rods the metal valve 70 disks or plates 15 and 16 respectively are fixed and upon the bottom face of each of said plates the leather or rubber washer 17 is secured for contact upon the valve seats. The valve rod 13 extends a considerable distance below the bottom wall of the bucket and has its extremity angularly bent, as at 18 for a purpose to be hereinafter referred to. A funnel-shaped discharge neck 19 projects downwardly from the opening 8 in the 80 bottom wall of the bucket and may be fitted into the contracted mouth of a jar or other receptacle.

A diametrically disposed rod 20 is fixed in the wall of the bucket at its upper open end, 85 and upon this rod a sleeve 21 is loosely engaged and to the medial portion of this sleeve an operating element 22 is fixed. The lower portion of this element is relatively broad and to the same the upper ends of the wire 90 rods 23 are loosely connected at opposite sides of the sleeve 21 and in spaced relation thereto. The lower ends of the wire rods 23 are provided with elongated loops 24 which are engaged in loops 25 on the upper ends of 95 the respective valve rods 13 and 14. 26 designates a suitable bail or handle which is fixed at its ends to the upper or open end of the bucket.

In the practical operation of my improved 100 well bucket, it will be understood that when the bucket is lowered into the well, the water forces the valve disks or plates 15 and 16 upwardly and quickly fills the bucket. When 105 the bucket is raised, the valves automatically close so that the water is retained within the bucket. The contents of the bucket may be readily discharged by placing the same within a tub or other receptacle and the angular end 18 of the valve rod 13 striking the bottom of the receptacle forces the valve disk 15 upwardly so that the water may flow out of

the bucket through the discharge opening 7 in the bottom thereof. The valve may be retained in this position when the bucket is lifted from the receptacle by simply moving 5 the operating element 22 to the position indicated in dotted lines in Fig. 3. If it is desired to discharge the contents of the bucket into a jug or receptacle having a contracted mouth, the funnel spout or extension 17 is 10 fitted into the mouth of the receptacle and the element 22 moved to the position indicated in dash lines in Fig. 3 of the drawing so that the smaller valve plate 16 will be lifted to its open position. It will thus be seen 15 that it is not necessary to place the hand in the water to engage and lift the valve plates. The device is very serviceable and convenient in practical use and may be built in various sizes and dimensions so that it will properly 20 operate within tube or bored wells of various diameters.

While I have shown and described the preferred construction and arrangement of the several features of the bucket, it is to be 25 understood that the same is susceptible of considerable modification and I therefore reserve the privilege of adopting all such le-

gitimate changes as may be fairly embodied within the spirit and scope of the invention as claimed.

30

Having thus described this invention, what I claim is:—

A well bucket having spaced openings in its bottom wall, vertically movable rods, one of said rods extending through one of the 35 openings in the well bucket, valves rigidly fixed upon the respective rods to close said openings, spaced guides common to the two valve rods to maintain the same in coinciding axial relation with said openings, a lever 40 pivotally mounted within the upper end of the bucket, and rods connected to the upper ends of the valve rods for movement relative thereto, said latter rods being pivotally connected to the lever on relatively opposite 45 sides of its pivot, whereby the valves may be independently raised to open position when the lever is actuated.

In testimony whereof I hereunto affix my signature in the presence of two witnesses. 50

NOBLE G. BOWLES.
